UNITED STATES PATENT OFFICE.

ALEXANDER DOM, OF CINCINNATI, OHIO.

COMBINED HAND DRILL AND VALVE GRINDER.

Application filed March 13, 1923. Serial No. 624,848.

To all whom it may concern:

Be it known that I, ALEXANDER DOM, a citizen of the United States, residing at Cincinnati, in the county of Hamilton and State 5 of Ohio, have invented certain new and useful Improvements in Combined Hand Drills and Valve Grinders, of which the following is a specification.

My invention relates to combination hand 10 drills and valve grinders.

The objects of my invention are to provide a simple, efficient, convenient, economical and easily operated tool which may be used either as a hand drill or as a valve 15 grinder as occasion requires. As a drilling machine it operates as any other drilling machine, running forward continuously but when adjusted for valve grinding the motion transmitted to the grinding tool is about 20 two turns forward to one reverse with the continuous forward motion of the operating handle.

My invention consists in a frame in which is mounted a shaft carrying two gears loosely 25 mounted and two clutches keyed thereon and slidably mounted and adapted to be shifted into and out of engagement with said gears by a shifting plate, said gears being operated by a large ring gear within which is 30 mounted an adjustable track which in its inner or contracted adjustment forms a circular grooved track which holds the shifting mechanism in continuous forward action and when adjusted for alternating reversible motion, such as valve grinding, the form 35 of the grooved track is oblong with a curve at each end and forms a cam or its equivalent, causing the mechanism to oscillate from the forward driving gear to the reverse driving gear alternately, the shifting mechanism being so constructed that the forward motion has practically twice the motion of the reverse motion.

My invention also consists in the parts 40 and in the combination and arrangement of parts as herein set forth and claimed.

In the drawings:

Fig. 1 is a rear elevation of the device;

Fig. 2 is an inner face view of the ring 50 gear and slideable sector carried thereby forming part of my invention;

Fig. 3 is a plan view and side elevation of the clutch shifter;

Fig. 4 is a front elevation of the device 55 after the ring gear has been removed;

Fig. 5 is a side elevation of the device;

Fig. 6 is a front elevation of the device;

Fig. 7 is a longitudinal section of the device;

Fig. 8 is a front elevation of the device 60 showing it in position for use in grinding valves on an automobile;

Fig. 9 is a perspective view of the slideable sector mounted in the ring gear;

Fig. 10 is an inner face view of the ring 65 gear indicated by dotted lines with the adjusted sector adjusted to form a circular track for use in drilling; and

Fig. 11 is a similar view with the adjustable sector in extended position to form an 70 oblong track whereby an alternately reversible motion is obtained for valve grinding and the like.

In the embodiment of my invention as 75 illustrated and which shows a preferred construction the frame 1 comprises spaced apart sides 2 and 3 which are connected at one end to tubular bearing 4 and at the other end to tubular bearing 5 on which handle 6 is mounted. Said sides 2 and 3 are centrally 80 connected by cross support 7 having tubular opening 8 extending transversely therethrough in alignment with bearings 4 and 5 and having upon one side a boss 9 with flattened sides 10 and 11. A hollow internally 85 threaded stud 12 extends outwardly from said boss.

The operating shaft 13 is rotatably mounted in frame 1 in hollow bearings 4 and 5 and preferably projects beyond bearing 4 for the 90 purpose of attaching a chuck 14 or other tool. Clutch gear 15 is rotatably mounted upon said shaft adjacent bearing 4 and a like clutch gear 16 is rotatably mounted on said shaft adjacent bearing 5 both within said frame. Each of said gears is so mounted on said shaft as to allow a minimum of longitudinal movement. Clutches 17 and 18 are 95 each slidably and non-rotatably mounted on shaft 13 between its respective clutch gear and cross support 7.

The clutch shifter 19, preferably of the form shown in Fig. 3, is slidably mounted on said frame, spanning boss 9 and having fingers 20 slidably engaging grooves 21 in 105 clutches 17 and 18. Said clutch shifter is of such length that when moved longitudinally to bring one of the clutches out of operative engagement with its clutch gear it will bring the other clutch into operative engagement 110 with the other clutch gear. Pin 22, preferably of small diameter, is fixed on the face

of clutch shifter 19 and is preferably provided with an anti-friction roller 23.

Ring gear 24 is mounted on boss 9 and stud 12 which latter extends through central bearing 25, said ring gear being in operative engagement with said clutch gears. The inner face of ring gear 24 is provided with recess 26 of peculiar shape and having curved and straight surfaces and so formed that adjustable sector 27, clearly shown in Fig. 9, mounted therein forms a circular bearing or track 28 when adjusted to contracted position and forms oblong bearing or track 29 when adjusted to its extended position. Said sector is provided with an arc-shaped member 30 having flat faces 31 and 32 to slidably engage corresponding flat faces 33 and 34 respectively, formed on the wall of said recess. A U-shaped cam 35 is supported by said arc-shaped member in spaced apart relation therewith and spans boss 36 centrally formed in ring gear 24. Thumb screw 37 extending through slot 38 is mounted in sector 27 for the purpose of holding said sector in either contracted or expanded position. The ring gear is held in assembled relation with the other parts of the device by means of screw 39 secured in the end of stud 12. A suitable operating handle 40 is fixed upon ring gear 24 and preferably extends beyond the periphery thereof.

When it is desired to operate the device as a hand drill the sector is adjusted to the position shown by dotted lines in Fig. 2 or to the position shown by full lines in Fig. 10 thereby forming a circular track and causing the operating shaft to move continuously in one direction only. When it is desired to adjust the device to obtain an alternating reversible motion of the shaft, as in valve grinding, merely loosen screw 39 and adjust the sector to the position shown by full lines in Figs. 2 and 11 and again tighten the thumb screw thereby forming an oblong track bringing cam 35 into operative position whereby an alternating reversible motion is produced.

When in its contracted position the roller 23 travels in the circular groove as indicated by dotted lines in Fig. 10, and causes no oscillation of clutch shifter 19 but in its expanded or extended position roller 23 travels in the oblong groove in the path indicated by dotted lines in Fig. 11 and oscillates said clutch shifter 19 thereby carrying clutches 17 and 18 into and out of engagement alternately with the two clutch gears thereby intermittently reversing the motion of the operating tool which is essential and necessary for satisfactory valve grinding. In grinding valves with this tool it is held in engagement with the valve by one hand (see Fig. 8) and by turning handle 40 in one direction only with the other hand a uniform forward and reverse movement of the valve on its seat is obtained, approximately two

turns forward to one reverse to each revolution of the handle 40.

Valves were first ground by holding a screw driver in vertical position between the hands and rotating it several times forward and backward and then, after taking a new hold, repeating the operation, suggesting the desirability of motion obtaining the alternating reversible motion of different proportions for the purpose of avoiding 75 grooving of the valve seats and to secure a perfectly smooth air or gas tight seat. I accomplish this result mechanically and secure uniformity of action in the operation by means of my construction. 80

An advantage of my invention is in providing a tool that will do this work perfectly in combination with an original standard equipped hand drill thereby greatly economizing in the cost of the tool for both purposes. 85

While I have shown and described a particular construction and arrangement of parts it will be apparent that various modifications may be made without departing from its 90 scope or spirit as defined in the claims.

What I claim as new and desire to secure by Letters Patent is:

1. In a combined hand drill and valve grinder, a frame, a shaft rotatably mounted in said frame, clutch gears each rotatably mounted on said shaft, clutches each slidably and non-rotatably mounted on said shaft and adapted to engage or disengage its adjacent clutch gear, a clutch shifter 95 in said frame, clutch shifter, a ring gear provided on said clutch shifter, operating means on said clutch shifter, a ring gear provided with suitable operating means and mounted in engagement with said clutch gears and having means therein to form either a circular or an oblong track, as desired, to engage said operating means whereby when said ring gear is turned continuously in one direction said shaft will be driven continuously in one direction also when said track is adjusted to circular form, but will have an alternating reversible motion when said track is extended to oblong form. 100

2. In a combined hand drill and valve grinder, a frame, a shaft rotatably mounted in said frame, clutch gears each rotatably mounted on said shaft, clutches each slidably and non-rotatably mounted on said shaft and adapted to engage or disengage its adjacent clutch gear, a clutch shifter 115 engaging said clutches, a pin or roller on said clutch shifter, a ring gear provided with suitable operating means and mounted in engagement with said clutch gears and having means therein to form either a circular or an oblong track, as desired, to engage said operating means whereby when said ring gear is turned continuously in one direction said shaft will be driven continuously in one direction also when said track 120 125 130

is adjusted to circular form, but will have an alternating reversible motion when said track is extended to oblong form.

3. In a combined hand drill and valve grinder, a frame, a shaft rotatably mounted in said frame, clutch gears each rotatably mounted on said shaft, clutches each slidably and non-rotatably mounted on said shaft and adapted to engage or disengage its adjacent clutch gear, a clutch shifter engaging said clutches, operating means on said clutch shifter, a ring gear mounted in engagement with said clutch gears and having a recess therein provided with straight walls and curved walls, an adjustable sector having curved walls and straight walls and means to hold said sector in adjusted position to form either a circular track or an elongated track having curved ends to engage said operating means whereby when said ring gear is turned continuously in one direction said shaft will be driven continuously in one direction also when said sector is in contracted position, but will have an alternating reversible motion when said sector is adjusted to elongated or extended position.

4. In a combined hand drill and valve grinder, a frame having bearings, a handle on said frame, a rotatable shaft in said bearings, clutch gears each rotatably mounted on said shaft, clutches each slidably and non-rotatably mounted on said shaft and adapted to engage or disengage its adjacent clutch gear, a clutch shifter engaging said clutches, operating means on said clutch shifter, a ring gear provided with suitable operating means and mounted in engagement with said clutch gears and having means therein to form either a circular track or an oblong track, as desired, to engage said operating means whereby when said ring gear is turned continuously in one direction said shaft will be driven continuously in one direction also when said track is adjusted to circular form, but will have an alternating reversible motion when said track is extended to oblong form.

5. In a combined hand drill and valve grinder, a frame having a bearing at each end, a cross support centrally of said frame and having a tubular opening extending transversely therethrough, a shaft rotatably mounted in said bearings, clutch gears each rotatably mounted on said shaft, clutches each slidably and non-rotatably mounted on said shaft and adapted to engage or disengage its adjacent clutch gear, a clutch shifter engaging said clutches, operating means on said clutch shifter, a ring gear provided with suitable operating means and mounted in engagement with said clutch gears and having means therein to form either a circular track or an oblong track, as desired, to engage said operating means

whereby when said ring gear is turned continuously in one direction said shaft will be driven continuously in one direction also when said track is adjusted to circular form, but will have an alternating reversible motion when said track is extended to oblong form.

6. In a combined hand drill and valve grinder, a frame having a central bearing and a bearing at each end, a handle on said frame, a shaft rotatably mounted in said bearings, clutch gears each rotatably mounted on said shaft, clutches each slidably and non-rotatably mounted on said shaft and adapted to engage or disengage its adjacent clutch gear, a clutch shifter engaging said clutches and comprising a slotted plate having means at each end adapted to engage said clutches, operating means on said clutch shifter, a ring gear provided with suitable operating means and mounted in engagement with said clutch gears and having means to form either a circular track or an oblong track, as desired, to engage said operating means whereby when said ring gear is turned continuously in one direction said shaft will be driven continuously in one direction also when said track is adjusted to circular form, but will have an alternating reversible motion when said track is extended to oblong form.

7. In a combined hand drill and valve grinder, a frame comprising spaced apart sides connected at one end to a hollow stem and at the other end to a tubular bearing and having a cross support centrally connecting said sides with a tubular opening extending transversely therethrough, a stud mounted on said support, a rotatably mounted shaft in said bearings, clutch gears each rotatably mounted on said shaft, clutches each slidably and non-rotatably mounted on said shaft and adapted to engage or disengage its adjacent clutch gear, a clutch shifter engaging said clutches, operating means on said clutch shifter, a ring gear provided with suitable operating means and mounted on said stud in engagement with said clutch gears and having means therein to form either a circular track or an oblong track, as desired, to engage said operating means whereby when said ring gear is turned continuously in one direction said shaft will be driven continuously in one direction also when said track is adjusted to circular form, but will have an alternating reversible motion when said track is extended to oblong form.

8. In a combined hand drill and valve grinder, a frame, a shaft rotatably mounted in said frame, clutch gears each rotatably mounted on said shaft, clutches each slidably and non-rotatably mounted on said shaft and adapted to engage or disengage said clutch gear, a clutch shifter engaging

- said clutches, operating means on said clutch shifter, a ring gear mounted in engagement with said clutch gears and having a recess in its inner face, a sector having a cam and mounted in said recess and adapted to be adjusted to contracted position to form a circular bearing or track engaged by said operating means to produce a continuous rotary motion of said shaft or to be extended to oblong position to form an oblong bearing or track to produce an alternating reversible motion of said shaft, and means for operating said ring gear continuously in one direction.
15. 9. In a combined hand drill and valve grinder, a frame, a rotatably mounted shaft in said frame, clutch gears each rotatably mounted on said shaft, clutches each slidably and non-rotatably mounted on said shaft and adapted to engage or disengage its adjacent clutch gear, a cross support on said frame, a boss on said support, a stud on said boss, a clutch shifter spanning said boss and adapted to move said clutches into and out of operative engagement respectively, operating means on said shifter, a ring gear provided with suitable operating means and mounted on said stud in engagement with said clutch gears and having means therein to form either a circular track or an oblong track, as desired, to engage said operating means whereby when said ring gear is turned continuously in one direction said shaft will be driven continuously in one direction also when said track is adjusted to circular form but will have an alternating reversible motion when said track is extended to oblong form and means to hold said ring gear in operative position on said stud.
40. 10. In a combined hand drill and valve grinder, a frame, a shaft rotatably mounted in said frame, clutch gears each rotatably mounted on said shaft, clutches slidably and non-rotatably mounted on said shaft, and adapted to engage or disengage its adjacent clutch gear, a clutch shifter slidably engaging said clutch, operating means on said clutch shifter, a ring gear provided with suitable operating means and mounted in engagement with said clutch gears and having means therein to form either a circular track or an oblong track, as desired, to engage said operating means whereby when said ring gear is turned continuously in one direction said shaft will be driven continuously in one direction also when said track is adjusted to circular form but will have an alternating reversible motion when said track is extended to oblong form.
45. 11. In a combined hand drill and valve grinder, a frame, a shaft rotatably mounted in said frame, clutch gears each rotatably mounted on said shaft, clutches each slidably and non-rotatably mounted on said shaft and adapted to engage or disengage its adjacent clutch gear, a clutch shifter having means at each end engaging said clutches, operating means on said clutch shifter, a ring gear provided with suitable operating means and mounted in engagement with said clutch gears and having means therein to form either a circular track or an oblong track, as desired, to engage said operating means whereby when said ring gear is turned continuously in one direction said shaft will be driven continuously in one direction also when said track is adjusted to circular form but will have an alternating reversible motion when said track is extended to oblong form.
50. 12. In a combined hand drill and valve grinder, a frame, a shaft rotatably mounted in said frame, clutch gears each rotatably mounted on said shaft, clutches each slidably and non-rotatably mounted on said shaft and adapted to engage or disengage its adjacent clutch gear, a clutch shifter having fingers adapted to engage said clutches, operating means on said clutch shifter, a ring gear provided with suitable operating means and mounted in engagement with said clutch gears and having means therein to form either a circular track or an oblong track, as desired, to engage said operating means whereby when said ring gear is turned continuously in one direction said shaft will be driven continuously in one direction also when said track is adjusted to circular form but will have an alternating reversible motion when said track is extended to oblong form.
55. 13. In a combined hand drill and valve grinder, a frame, a shaft rotatably mounted in said frame, clutch gears each rotatably mounted on said shaft and adapted to engage or disengage said clutches, a clutch shifter engaging said clutches, operating means on said clutch shifter, a ring gear mounted in engagement with said clutch gears and having a recess in its inner face, a sector having a cam, and mounted in said recess and adapted to be adjusted to contracted position to form a circular bearing or track to produce a continuous rotary motion of said shaft or to be adjusted to extended position to form an oblong bearing or track engaged by said operating means to produce an alternating reversible motion of said shaft, and means for operating said ring gear continuously in one direction.

ALEXANDER DOM.
